CROSS STRETCH FOUNDATION GARMENT

Caroline Brown, New York, N. Y.

Application July 20, 1946, Serial No. 685,090

3 Claims. (Cl. 2-37)

1

This invention relates to foundation garments. Broadly, it is an object of my invention to provide a foundation garment which will give desired support to the abdominal region without obstructing movement of the legs.

More particularly, it is an object of my invention to provide a foundation garment which will result in a series of forces so that the different desired parts of the body will be aided and supported without restricting the muscles and movement of the person. In my Patent No. 2,052,163 I have discussed such forces.

A further object is to provide a garment which will exert an arcuate force to cradle and support the gluteus maximus muscles and divergent forces to draw an abdominal panel inwardly to support the entire abdominal region.

Still a further object is to provide a comparatively simple and inexpensive foundation garment for both cold and warm climate which will give the desired support and at the same time present a neat and refined appearance.

For a fuller understanding of the nature and objects of my invention reference is had to the following detailed description in connection with the accompanying drawings, in which:

Figure 1 is a front view of a foundation garment.

Figure 2 is a rear view thereof.

Figure 3 is a side view thereof.

Figure 4 is a side view of a modified foundation garment.

Referring to Figures 1 to 4, inclusive, numeral 10 represents a foundation garment having a front panel 11 made of non-stretchable material, the lower edge of which is on a line with the groin while the upper central point extends to a point between the breasts. Panel 11 is substantially a vertical rectangle, except for the upper line which terminates in a central point between the breasts as just described. Attached at each side and along the entire length of the vertical edges of the front panel 11 is lower left side elastic band 12 and lower right side elastic band 13 which stretch diagonally downward and around the hips and are attached at their lower ends to the lower part of rear member 16 by stitching 17 and 18, respectively.

Rear member 16 is made of two way stretch elastic material, as indicated by the arrows in Figure 2, the upper edge of which is slightly higher than the small of the back and the lower part covers the pelvis region.

Also attached at each side and along the entire length of the vertical edges of the front panel

2

11 is upper right side elastic band 14 and upper left side elastic band 15 which stretch diagonally upward and are attached at their lower ends to the rear member 16 by stitching 19 and 20, respectively. The upper bands 14 and 15 and the lower bands 12 and 13 cross one another along the entire length of the front panel 11.

Lower band 12 has its edge 21 free while lower band 13 has its edge 22 free. Upper band 14 has its edge 23 free while upper band 15 has its edge 24 free. The extreme lower points of elastic bands 12, 13, 14 and 15 are attached to the front panel 11 at the groin as indicated by numeral 56 in Figure 1.

15 A bra 25 is attached to the upper part of the front panel 11 and the upper part of elastic bands 14 and 15. Shoulder straps 26 are attached to the bra at the front and to the upper edge of rear member 16. Side straps 29 may be attached to shoulder straps 26 and to bands 14 and 15, as shown. Attached to the bottom edge of rear member 16 are rear garters 27 which are fastened to the hose. Side garters 28 are diagonally attached to the lower edges of bands 12 and 13 for fastening to the hose.

20 Referring to Figure 4, this modified foundation garment is alike in every respect to that of Figures 1, 2 and 3, except that back member 30 is cut vertically at the side. Upper side elastic band 31 and lower side elastic band 32 are cut along a vertical line at the side and are attached along a vertical line by stitching 33.

25 The two headed arrows represent the directional stretch or pull of the elastic members or bands while the single headed arrows represent the resulting forces at approximately the points where indicated or applied. It will thus be seen that the diagonal pull of the elastic bands 12 to 15, inclusive, supports the front panel 11 and thus gives support to the abdominal region. Since the front panel 11 does not reach below the groin line, the greatest freedom of movement is given to the legs.

30 It is obvious that various modifications and changes may be made in the details of construction without departing from the general spirit of the invention.

I claim:

35 1. A foundation garment of the character described, a front panel of non-stretchable material, the bottom horizontal edge of which is approximately on a line with the groin, a rear elastic member the greater portion of which is below the small of the back, elastic opposed lower side members attached along the entire length of the

side edges of said front panel and stretching diagonally downward and around the hips and attached to said rear member, elastic opposed upper side members attached along the entire length of the side edges of said front panel and stretching diagonally upward and around the waist and attached to said rear member, said upper and lower members crossing one another at the sides, and a bra attached to the upper part of said garment.

2. In a foundation garment of the character described a front panel of non-stretchable material the lower edge of which is on line with the groin and the upper central point extending to a point between the breasts, a rear member, elastic lower side members attached along the entire length of the vertical edges of said front panel and stretching diagonally downward and around the hips and attached to said rear member, elastic upper side members attached along the entire length of said vertical edges of said front panel, said upper and lower members crossing one another along the entire length of said front panel, said upper side members attached to said rear member, a bra and shoulder straps attached to the upper portion of said garment and garters attached at the lower portion of said lower side members whereby a force is exerted upon said front panel for the support of the abdominal region without obstructing movement of the legs.

3. In a foundation garment of the character described, a non-stretchable front panel beginning at the groin and extending to the breast region,

an elastic rear member, elastic lower side members attached along the entire length of the vertical edges of said front panel and stretching diagonally downward around the hips and attached to said rear member, elastic upper side members attached along the entire length of the vertical edges of said front panel and stretching diagonally upward and attached to said rear member, said upper and lower side members crossing one another at the front, a bra attached at the upper portion of said garment, shoulder straps attached to said bra and at the rear of said garment, side straps attached to said shoulder straps and said upper side members and garters attached to the lower edges of said lower side members.
